Primary Examiner — Rashida Johnson(74) *Attorney, Agent, or Firm* — Mario Theriault(57) **CLAIM**

The ornamental design for a hospital gown, as shown and described.

DESCRIPTION

FIG. 1 is a front perspective view of a hospital gown, showing a first embodiment of my new design;

FIG. 2 is a front view thereof;

FIG. 3 is a back view thereof;

FIG. 4 is a front perspective view of a hospital gown, showing a second embodiment of my new design;

FIG. 5 is a front view of the second variant of my design; and, FIG. 6 is a back view of the second variant of my design.

The broken lines shown in FIGS. 1-6 represent stitching.
